PATENTED DEC. 18, 1906.

W. VAN BUSKIRK.

MACHINE FOR GUMMING OR SETTING SAWS.

APPLICATION FILED FEB. 24, 1906.

UNITED STATES PATENT OFFICE.

WILLIAM VAN BUSKIRK, OF ST. JOSEPH, MISSOURI.

MACHINE FOR GUMMING OR SETTING SAWS.

No. 838,595.

Specification of Letters Patent.

Patented Dec. 18, 1906.

Application filed February 24, 1905. Serial No. 247,148.

To all whom it may concern:

Be it known that I, WILLIAM VAN BUSKIRK, of St. Joseph, in the county of Buchanan and State of Missouri, have invented 5 certain new and useful Improvements in Machines for Gumming or Setting Saws, of which the following is a specification.

My invention relates particularly to saw-gumming machines, and has for its object 10 the production of a die-cutting machine of that class which, besides being simple and economical of manufacture, combines efficiency and accuracy of operation with facility of operation and variability of range of work. In respect to range of work my machine may not only be readily adapted as a 15 gumming-machine to cut teeth of different depth or shape, but also may be conveniently adapted for setting saws and the like. 20 In the accompanying drawings, which constitute a part of this specification, and wherein I show my invention in form of embodiment of a saw-gummer, Figure I is a perspective view of my machine in the open position ready to receive and operate upon a saw. Fig. II is a side elevation of the same, showing the machine in operative relation to a saw in place upon the die or counter, the 25 extremity of the lever-handle being broken away. Fig. III is a central vertical section, partly broken away, showing the base-plate, punch, punch-bar, and die or counter in their relative operative positions. Fig. IV is a detail sectional view illustrative of special cutting edges of the die. Fig. V is a detail plan view showing one form of cutting edges of the punch.

Referring to the numerals on the drawings, 1 indicates the base-plate or base-bar 40 of the machine, which is preferably provided with a foot-piece 2, adapted under pressure of the foot of an operator to maintain the machine in position advantageous for operation, particularly in respect to strain applied in practice upon the lever-handle 3, which is pivoted to the member 1 as on the pin 4 between lugs 5, formed as by bifurcation of the member 1. The member 1 is designated the "base-plate" or "base-bar" of 45 the machine, because it supports directly the impress-receiving member—to wit, the die or counter 6—which sustains the operative strain of the machine and which is for that purpose provided with one or more, and 50 preferably, as hereinafter specified, a plurality of, apertures or clefts 7 and 8, against the

cutting edges 9 whereof the cutting edges 10 of a properly-gaged and suitably-actuated rocking punch 11 coöperate shearwise. It is by variation of the shape of the cutting 6c edges of the punch 11 and its counter 6 that the work which the machine is adapted to do may be varied.

By slight variations of the form of the impress-receiving member the function of 65 the machine may be varied, as has been suggested, from that of a gumming or punching machine, as illustrated, to a setting-machine. Moreover, by providing a die 6 with a plurality of clefts 7 and 8, which is the preferred 70 structure of my machine, as hereinbefore set forth, and by mounting the die movably upon the base-plate 1 the adaptability of the machine may be materially augmented. It may, for example, be in the manner de- 75 scribed adapted for gumming saw-teeth of variable contour, as in the M-tooth saw illustrated in Fig. II of the drawings. I prefer to mount the member 6 revolvably upon the base-plate 1, as by a screw 15 passing through 80 an aperture in the middle of the die 6 and entering a threaded aperture provided for it in the base-plate. By this means the member 6 may be secured movably in place or detached for the substitution of another die 85 conveniently and as often as required.

The punch 11 is operatively mounted in a punch-bar 16, that is operatively connected with the lever-handle 3 and to the base-plate 1. With the object of securing multiplied 90 leverage the punch-bar is pivoted, as indicated at 17, to a link 18, that is pivoted, as indicated at 19, to the handle 3, while the end of the bar 16 opposite to its pivotal member 17 is pivoted to the base-plate 1 ap- 95 proximately at the end thereof that is opposite to the pivotal connection 4 between the base-plate and the handle 3. In the construction specified the punch-bar 16 is of greater longitudinal extent from its point of 100 pivotal connection than the base-plate 1, thereby throwing the pivot 17 beyond vertical alignment with the pivot 4 and securing for the operative leverage upon the bar 16 the great preponderance of the long arm of 105 the lever-handle 3 as compared with its short arm, which is measured by the distance between the pivotal members 4 and 19.

A convenient structural feature of my machine is shown in the means employed for 110 mounting the punch-bar 16 pivotally upon the base-plate 1. It consists in splitting or

- cleaving the body of the base-plate, which is made of a considerable weight of metal, as indicated at 20, to form the foot-piece 2, previously specified, and the bearing member 21. (See particularly Fig. III.) The bearing member is preferably bifurcated to form jaws 22 and 23, which support the bearing-pin 24, upon which the punch-bar 16 is mounted, as heretofore suggested.
- 10 The bearing member 21 and the punch-bar 16 adjacent to its pivotal connection therewith are oppositely curved, as illustrated, in order to provide suitable space for the play of the punch 11 for the performance of its 15 shearwise-cutting function and for imparting to it the desired direction of movement. The operative movement of the punch 11, which the shapes of its operative actuating members last referred to are designed to accommodate, is characterized by a rocking movement in large measure determined by the shape of the punch itself, which being, in effect, a lever as well as a shearing member constitutes an important factor in the efficient 25 operation of the machine. Using the term "punch" in the broad sense of an impress-presenting member as correlated to the impress-receiving member 6 previously specified, I define it in its preferred form of embodiment to be a lever or bar having a rounded heel 25, which during its movement of actual operation rides upon the face of the base-plate 1 and having a toe-piece 26, which under impulse of the bar 16 coöperates with the heel 25 to actuate it. Nearer the heel 25 than the toe-piece 26 the punch is provided with a supporting-lug 27, which entering a recess 28 in the under side of the punch-bar 16 (see Fig. III) is secured loosely therein, as 30 by a loose transverse pin 30. The pin 30 may be loosely inserted, because, as will presently be made to appear, it has to sustain but little stress in operation, and it is loosely inserted in order to facilitate the substitution of one punch for another as often as 35 wear or the change or readjustment of the die 6 may require.
- In operation the lever 3 is lifted toward a position at right angles with the base-plate 1, 40 as shown in Fig. I, in which position the punch-bar 16, by reason of its curvature and the curvature of its bearing member 21, is lifted sufficiently not only to permit the toe-piece 26 by gravity to drop toward the die 6, 45 but also to raise the heel 25 of the upper face of the die sufficiently to admit of the introduction of the object to be operated upon. (Illustrated in Fig. II as a saw-blade 31.) If from the position shown in Fig. I the handle 3 50 be pressed toward its position shown in Fig. II, which is the same as that which it would occupy in Fig. III if Fig. III afforded complete illustration of the machine, the heel 25 is first presented against the face of the base-plate 1, which thereupon becomes the main

bearing-point for its continued rotative movement. Its working movement is derived from depression of the lever-handle 3 through engagement of the toe-piece 26 with the under side of the punch-bar 16, and the punch 70 becoming, in effect, an integral part of the punch-bar and working solidly with true shearwise action against the cutting edges of its die it performs the function required of the machine with perfect efficiency and accuracy. It may be observed that the pin 30, fitting loosely within the aperture provided for it within the lug 27, does not receive the strain of pressure in operation, but that the strain is distributed among the heel 25, toe-piece 26, lug 27, and the points of contact between those several members and the base-plate and punch-bar, respectively.

The material of which my machine is constructed may be of iron or steel, with the exception of the impress presenting and receiving members, which are preferably of suitably-hardened steel, it being quite obvious that the impress presenting and receiving members, respectively, may be varied from 80 their function of cutting members to swaging or bending or setting members.

The cutting edges 9 of the clefts of the die or counter 6 are of special construction, being everted or uplifted above the surface of 95 the die, as clearly illustrated in Fig. IV of the drawings. This feature of construction is important, because it prevents bending of the saw-blade under the gumming operation, the everted edges serving to support the 100 blade exclusively and effecting a true and even shearwise cut against it.

Further specification of details appears to be unnecessary, it being my purpose to have it distinctly understood that I do not intend 105 to confine myself to details of construction, but to reserve the right to modify and vary the same at will within the scope of my invention as defined by the appended claims in view of the art to which the invention appertains.

What I claim is—

1. In a machine of the kind described, the combination with a base-plate, punch-bar, and means for actuating the same, of a punch including a toe-piece loosely mounted on the 115 punch-bar, and a heel upon the punch adapted in operation to ride upon the base-plate, the heel-piece and the toe-piece being at opposite ends of the punch.

2. In a machine of the kind described, the combination with a base-plate, punch-bar, and means for actuating the same, of a punch loosely mounted on the punch-bar, a heel upon the punch adapted in operation to ride upon the base-plate, and a toe-piece on the 125 punch adapted to operatively engage the punch-bar.

3. In a machine of the kind described, the combination with a base-plate, punch-bar, and means for actuating the same, of a die 130

upon the base-plate, a lever loosely pivoted to the punch-bar nearer one end thereof, said lever being provided, in operation, with bearings against the punch-bar and the base-plate, respectively.

- 5 4. In a machine of the kind described, the combination with a base-plate, punch-bar, and means for actuating the same, of a die upon the base-plate, and a punch loosely secured to the punch-bar by a pin, said punch being provided in operation with a bearing against the base-plate, and with a bearing against the punch-bar independent of said pin.
- 10 5. In a machine of the kind described, the combination with a base-plate, of a punch-bar pivoted to one end thereof, a lever piv-

oted to the other end thereof, a link connection between the free end of said punch-bar and said lever, a die movably mounted on 20 said base-plate and a punch loosely pivoted to said punch-bar and provided with a heel adapted in operation to rest on said base-plate near the pivot-pin of said punch-bar, and a toe adapted in operation to engage the 25 under side of said punch-bar whereby a very powerful shearing cut is obtained.

In testimony whereof I have hereunto signed my name in the presence of two subscribing witnesses.

WILLIAM VAN BUSKIRK.

Witnesses:

THEO RIESENMEY,
JOHN M. STAUBER.
